UNITED STATES PATENT OFFICE.

MORRIS OZLEK, OF PHILADELPHIA, PENNSYLVANIA.

HEAD CONSTRUCTION FOR ELECTRIC LAMPS.

1,355,163.

Specification of Letters Patent. Patented Oct. 12, 1920.

Application filed September 17, 1917. Serial No. 191,867.

To all whom it may concern:

Be it known that I, MORRIS OZLEK, a citizen of the United States, residing at Philadelphia, in the county of Philadelphia and State of Pennsylvania, have invented certain new and useful Improvements in Head Constructions for Electric Lamps, of which the following is a specification.

One object of my invention is to so construct an electric lamp head that the lamp sockets can be securely attached and so that the shade can be easily and quickly placed thereon and removed therefrom without the assistance of any clamping means.

15 A further object is to so design my invention that it will be durable and can be quickly made and assembled.

These objects, and other advantageous ends which will be described hereinafter, I 20 attain in the following manner, reference being had to the accompanying drawings in which—

Figure 1 is an elevation partly in section showing my improved lamp and how the 25 shade is mounted thereon.

Fig. 2 is a fragmentary section taken on the line 2—2 of Fig. 1.

Fig. 3 is a top plan view of my invention as shown in Fig. 2 with the top section removed.

Referring to the drawings, 1 represents a standard which is preferably made of wood and which may have any form of base, since the specific construction of the latter does 35 not form a part of my invention.

The upper end of the standard 1 is made cylindrical as shown at 2 to fit in a cylindrical bore 3 in a base section 4 of a head 5, preferably made of wood. The standard is 40 also provided with a collar 6, preferably made integral therewith which forms a support for the bottom of the section 4.

The section 4 has an annular flange 7, at the top, of relatively greater diameter than 45 the bottom portion of said section. The top surface of the section 4 has a recess 8 depending therein and a hole 9 communicates with this passage and with the cylindrical bore 3. The standard 1 is made hollow and 50 the electric supply wire 10 for the lamp extends through the hollow standard 1, hole 9, and into the recess 8.

The head 5 has a top section 11 and is of a 55 diameter considerably greater than the largest diameter of the section 4. The top section 11 is made comparatively flat as

clearly shown in Figs. 1 and 2 and has a shallow annular cavity 12 cut in its bottom surface 13. The upper portion of the annular flange 7 of the bottom section 4 fits within the cavity 12 and screws 7^a extend upwardly through the flange 7 into the section 11 as clearly shown in Fig. 2. Thus, the bottom section and top section are detachably secured together and the heads of the 60 screws being inverted, are practically invisible.

The section 11 also has a recess 14 extending inwardly from the cavity 12 and which co-acts with the recess 8 to provide a chamber 15 within the head. The section 11 has a thin circumferentially extending rim 16, the bottom of said rim being coincident with the bottom surface 13.

The rim 16 is comparatively wide and as 75 illustrated is located a considerable distance below the top surface 17 of the section 11. Thus, a secure and rigid support is produced for a ring 18 supporting the shade 19. The ring 18 is connected to the shade and 80 forms a part of its frame as clearly shown in Fig. 1.

Threaded sleeves 20 extend through the section 4, and at their inner ends are provided with nuts 21 which engage and have 85 their bearing upon the tapered side 22 of the recess 8. The outer ends of the sleeves 20 form the support for the electric sockets 23. The electric wire 10 is housed within the chamber 15 and has branches 24 and 25 90 which extend through the chamber 15 and downwardly through the sleeves 20 to the respective sockets 23 to supply the electric current to the electric bulbs 26.

The edge surface 27 of the top section 11 95 is frusto-conical in shape and therefore has a slight upward taper to facilitate the placement of the ring 18 thereover and so that it rests snugly between the surface 17 and the top of the rim 16. Furthermore by 100 making the surface 27 of frusto-conical shape, it will serve to support lamp shade securing rings 18 of various diameters and the weight of the lamp shade supporting ring engaging the tapered surface will bind 105 the ring to the top section of the head and thereby prevent the swinging of the shade on the head. By providing the extended rim 16, any lamp shade supporting rings which are of greater diameter than the 110 largest diameter of the surface 27 can be supported by said rim 16.

The internal diameter of the ring 18 is preferably made equal to the greatest diameter of the section 11 above the rim 16. However, if the diameter of the ring varies 5 either smaller or greater, the top section is capable of securely supporting the same in view of the large diameter of the rim 16 and the gradually tapered edge surface 27.

To detach the top section 11, it is merely 10 necessary to remove the screws 7^a when the entire contents of the chamber 15 will be exposed for repair or any other purpose desired. It will thus be noted that the nuts 21 securely hold the sleeves and sockets in 15 position and there are no means necessary for securing or clamping the shade to the head.

While I have described my invention as 20 taking a particular form, it will be understood that the various parts of my invention may be changed without departing from the spirit thereof, and hence I do not limit myself to the precise construction set forth, but consider that I am at liberty to make 25 such changes and alterations as fairly come within the scope of the appended claim.

Having thus described my invention, what

I claim as new and desire to secure by Letters Patent is:

A lamp head including a lamp shade supporting top, said top including a frusto-conical portion terminating at its bottom in an annularly extending rim, the outer peripheral of said frusto-conical portion serving to support lamp shade securing rings 30 of various diameters due to the frusto-conical shape of said top portion, said peripheral surface being of comparatively great depth relative to the thickness of said lamp shade securing rings and extending at such 35 steep angle that the lamp shade securing rings cannot shift laterally when resting thereon, said rim serving to support the securing rings of lamp shades of larger diameter than the largest diameter of said frusto-conical portion; substantially as described.

In testimony whereof I have signed my name to this specification in the presence of two subscribing witnesses.

MORRIS OZLEK.
